(57) **CLAIM**

I claim the ornamental design for a bottle, as shown and described.

DESCRIPTION

FIG. 1 is an exploded perspective view of a bottle showing my new design.

FIG. 2 is an exploded front elevation view thereof; wherein the left side, right side, and back views are identical.

FIG. 3 is a perspective view thereof.

FIG. 4 is a front elevation view thereof; wherein the left side, right side, and back views are identical.

FIG. 5 is perspective view thereof, with the cap removed from the figure.

FIG. 6 is a bottom view thereof, with the bottle's body removed from the figure.

FIG. 7 is a top view thereof, with the cap removed from the figure; and,

FIG. 8 is a bottom view thereof, with the cap removed from the figure.

1 Claim, 6 Drawing Sheets
